UNITED STATES PATENT OFFICE

2,040,472

OPEN-HEARTH FURNACE

Louis C. Edgar, Swissvile, Pa.

Application September 27, 1934, Serial No. 745,825

2 Claims. (Cl. 263—15)

This invention relates to open-hearth furnaces, one of the objects being to construct an open-hearth so as to confine the heating flame to the surface of the bath and keep it away from the roof. Other objects may be inferred.

In the accompanying drawings:

Figure 1 is a horizontal section of a side of a furnace to which the invention is applied;

Figure 2 is a vertical section of the same;

Figure 3 is a cross-section taken from the line III—III in Figure 2;

Figure 4 is a cross-section taken from the line IV—IV in Figure 2.

This furnace includes the usual hearth 1 which carries the metal bath, a port 2 which alternately functions to discharge fuel and air over the bath and to remove the products of combustion, an up-and-down-take 3 from which the port 2 opens, and a nozzle 4 which points through 20 the port 2 toward the hearth.

When this side of the furnace is on heat, heated air is blown through the up-and-down-take 3 and a flow of fuel is discharged from the nozzle 4 through the port 2. Both the port and the nozzle are arranged at a downward angle in the hope that this will throw the flame against the bath and away from the roof of the furnace. This result is usually not obtained for the reason that combustion does not occur directly at the opening of the port, the flame playing about in the furnace in a more or less haphazard manner.

In the case of the furnace being described, two upright conical arches 5 and 6 are arranged in the port 2 so that they are spaced from the walls 35 and top of the latter and are centered over the center line of the nozzle 4. These arches have open bottoms that face the up-and-down-take and which are mainly in line therewith, and they converge in the discharging direction of the nozzle 4 so as to form tandem inspirators which cause the flow of fuel to asperate into itself the air coming from the up-and-down-take 3. Therefore, these arches provide a means for causing substantial portions of the air and fuel to intermix before 45 leaving the port 2, whereby an intense flame is obtained which is concentrated directly against the surface of the bath. Since the majority of

the gas and air are thus burned in a localized area, there is little danger of the flame reaching the roof. Furthermore, the converging shapes of the arches 5 and 6 tend to downwardly direct the resulting flow of intermixed air and fuel much more effectively than can be done only by the declination of the nozzle 4 and port 2.

The arches 5 and 6 are made of any suitable refractory and have hollow walls. Pipes 7 and 8 serve to introduce cooling fluid to the hollow walls 10 of these arches.

In addition to functioning as inspirators when this side of the furnace is on heat, these arches 5 and 6 function as baffles when the other side of the furnace is on heat and the products of combustion are discharging through the port 2. Because of their conical shape, their baffling action is such as to smooth out the gaseous flow and thus prevent or at least diminish the pocketing effects caused by the shape of the port 2 and its abrupt 20 right angular turn at the up-and-down-take 3.

I claim:

1. An open-hearth furnace including the combination of a port, an up-and-down-take from which said port opens, a fuel nozzle pointing 25 through said port toward the hearth of said furnace, and at least one upright conical arch that is arranged in said port so that it is spaced from the walls and top of the latter and is centered over the center line of said nozzle, said arch converging in the discharging direction of said nozzle and having an open bottom that faces said up-and-down-take and is at least mainly in line therewith.

2. An open-hearth furnace including the combination of a port, an up-and-down-take from which said port opens, a fuel nozzle pointing through said port toward the hearth of said furnace, and a plurality of conical arches that are arranged in said port so that they are spaced 40 from the walls and top of the latter and are centered over the center line of said nozzle, said arches converging in the discharging direction of said nozzle and having open bottoms that face said up-and-down-take and are at least mainly 45 in line therewith.

LOUIS C. EDGAR.
